UNITED STATES PATENT OFFICE.

EUGENE IRVING HANSON, OF NEW ROCHELLE, NEW YORK, AND ALFRED JACOB HEINKE, OF TOWACO, NEW JERSEY, ASSIGNEES TO H. R. MALLINSON & CO. INC., OF NEW YORK, N. Y., A CORPORATION OF DELAWARE.

DESIGN FOR A TEXTILE FABRIC OR SIMILAR ARTICLE OF MANUFACTURE.

Application filed December 31, 1923. Serial No. 8,215. Term of patent 3½ years.

To all whom it may concern:

Be it known that we, EUGENE IRVING HANSON, a resident of New Rochelle, in the county of Westchester, State of New York, and ALFRED JACOB HEINKE, a resident of Towaco, in the county of Morris, State of New Jersey, both citizens of the United States of America, have invented a new, original, and ornamental Design for Textile Fabric or Similar Article of Manufacture, of which the following is a specification, reference being had to the accompanying drawing, forming a part thereof, and showing a face view of a piece of textile fabric embodying our design.

The design is intended to be repeated on the fabric as shown.

We claim:

The ornamental design for a textile fabric or similar article of manufacture substantially as shown.

EUGENE IRVING HANSON.
ALFRED JACOB HEINKE.
